UNITED STATES PATENT OFFICE.

GEORGE A. LOWRY, OF EAST BOSTON, MASSACHUSETTS.

SUBMARINE-SIGNAL DEVICE.

1,124,768.

Specification of Letters Patent. Patented Jan. 12, 1915.

Application filed May 23, 1907. Serial No. 375,211.

To all whom it may concern:

Be it known that I, GEORGE A. LOWRY, a citizen of the United States, residing at East Boston, in the county of Suffolk and State of Massachusetts, have invented certain new and useful Improvements in Submarine-Signal Devices, of which the following is a specification.

This invention relates to means in sub-10 marine signal devices for producing an audible signal below the surface of the water, and more particularly to the type comprising a bell having a clapper for sounding the same, and the primary object of 15 the same is to provide improved means for automatically and systematically producing an audible signal below the surface of the water, the operation of which does not depend directly upon the action of the water 20 to sound the signal.

A further object is to construct a signal buoy provided with improved means for producing an audible signal below the surface of the water, and improved means 25 whereby the particular buoy may be identified by its signal.

A further object is to construct an improved buoy provided with a sub-marine audible signal apparatus, and improved 30 means for automatically gathering and storing sufficient energy by the action of the water to operate the signal and to release and utilize the power to operate the signal.

A further object is to construct a buoy 35 provided with a submerged gong including a hammer with improved means for locking the hammer and improved means for releasing and operating the hammer.

A further object is to provide an im-40 proved device of this character which will be simple, cheap and durable in construction and efficient in operation.

To the attainment of these ends and the accomplishment of other new and useful 45 objects as will appear, the invention consists in the features of novelty of construction, combination and arrangement of the several parts hereinafter more fully described and claimed, and shown in the accompanying 50 drawings illustrating an exemplification of the invention, and in which:—

Figure 1 is an elevation of an improvement of this character constructed in accordance with the principles of this invention. Fig. 2 is an enlarged detail sectional view on line 2—2 of Fig. 3. Fig. 3 is an ele-

vation of the operating mechanism, partly in section. Fig. 4 is a detail sectional view on line 4—4 of Fig. 3. Fig. 5 is a view similar to Fig. 4, showing the operating member in an adjusted position. Fig. 6 is an end elevation partly in section of the operating mechanism.

Referring more particularly to the drawings and in this exemplification of the invention, the numeral 10 designates a suitable buoyant body, such as a buoy or the like, which is adapted to float upon the water.

The numeral 11 designates a suitable tubular member of any desired size and secured to said member 11 is an arm 12 which is preferably spaced from the side thereof. The tubular member 11 is pivotally supported by the buoy 10 in any desired or suitable manner, preferably by means of a bar or rod 13, one end of which is preferably swiveled to the arm 12, as at 14, and the other end is pivotally connected to the buoy 10, as at 15. Disposed between the tubular member 11 and the arm 12, preferably at a point adjacent the lower extremity of the member 11, is a grooved pulley wheel 16 which is mounted for rotation upon a suitable axle 17 secured between the extremity of the arm 12 and the member 11. The pulley 16 is preferably provided with a laterally projecting portion 18 which is preferably provided with an undulating or scalloped periphery 19 for a purpose to be set forth. The tubular member 11 preferably projects for some distance below the pulley wheel 16, and secured to the extremity thereof is a bell 20. Secured also to the tubular member, preferably adjacent the pulley wheel 16, is a suitable bracket 21, and pivotally supported by the bracket is a retaining dog or pawl 22, one extremity of which is adapted to project through a suitable aperture or opening 23 in the tubular member 11 so as to engage suitable rack teeth 24 on a member 25, which latter is adapted to operate the signal in a manner to be set forth. This member 25 may be of any desired length and is of a sufficient weight to trip the bell hammer when it descends.

Pivoted on the bracket 21 is a suitable arm 26, to one end of which is pivoted a suitable dog 27, and said dog 27 is preferably located adjacent the retaining dog or pawl 22 and is also adapted to pro-

ject through the aperture or opening 23 in the tubular member 11 so as to engage the rack teeth 24 on the member 25. The free end of the arm 26 is preferably disposed at 5 an angle to the body portion thereof, as at 28, and journaled on said end 28 is a suitable antifriction roller 29, which is so disposed as to engage the undulated or scalloped periphery of the laterally projecting portion 18 on the pulley 16 so that when the pulley is rotated in either direction, a vibratory motion will be imparted to the arm 26 through the medium of the anti-friction roller 29 lying against the undulated or 15 scalloped periphery 19 of the portion 18.

A bell clapper or hammer 30 is preferably pivotally supported as at 31 to the bracket 21, and an arm 32 is connected to the bell clapper or hammer 30 adjacent the pivoted 20 point 31 thereof and is disposed at a substantial right angle thereto. Said arm is of such a length that the extremity thereof will project through a suitable slot or aperture 33 in the tubular member 11.

25 The member 25 is provided with lugs or projections 34, which are spaced from each other and preferably arranged behind the rack teeth 24. These lugs or projections 34 may be formed in any desired or suitable 30 manner, preferably by cutting away a portion of the rear face of the member 25. The arm 32 is of such a length as to project into the opening between the lugs 34 so that when the member 25 descends after having 35 been raised to its highest position, the lugs 34 will successively strike the extremity of the arm 32 to rock said arm to operate the bell clapper or hammer 30. The arm 32 is preferably provided with a pivoted latch 40 35, which is adapted to yield to permit the lugs or projections 34 to pass when the member 25 is raised, but when the member descends, the latch 35 will assume a position to be engaged by the lugs so as to rock the 45 arms 32.

A suitable flexible member 36, such as a chain, or the like, is adapted to pass over the pulley 16, and one end thereof is secured in any desired manner to a suitable 50 anchor 37 to maintain the buoy in its proper place. Secured to the free end of the flexible member 36 is a suitable weight 38.

The member 25 is adapted to be moved in the tubular member 11 and to assume a position within the lower extremity thereof. Assuming member 25 to be located within the lower extremity of the tubular member 11, it will be seen that when the buoy 10 rises on a wave, the pulley 16 will be caused 55 to rotate in one direction due to the action of the flexible member 36 thereof, one end of which latter is firmly anchored, and to the yielding action of the weight 38. When the buoy rides down or descends into the trough 60 65 of the sea, the tension will be released from

the weight 38, which latter is sufficient to draw the chain around the pulley 16 and cause the latter to revolve in an opposite direction so that an oscillatory motion would be imparted to the pulley as the buoy rises 70 and descends.

The rotation of the pulley 16, under the influence of the flexible member 36, will impart a similar motion to the laterally projecting portion 18, causing its undulated or 75 scalloped periphery 19 to engage the anti-friction roller 29 on the arm 26, which will vibrate the arm and cause the dog or pawl 27 to be raised and lowered. When the pawl 27 descends it will engage one of the rack 80 teeth 24, and when it rises will elevate the member 25, which latter will be held in its elevated position by means of the retaining dog or pawl 22. This operation is continued until the member 25 has reached the 85 limit of its upward movement, that is, until the retaining dog or pawl 22 is in engagement with the lowermost rack tooth 24.

The teeth 24 which stand adjacent the dog or pawl 27 when the member 25 is at the 90 limit of its upward movement, is preferably provided with an inclined or beveled face 39, so that when the parts are in this position and a further rotation is imparted to the pulley 16, the dog or pawl 27 will engage 95 the inclined or beveled face 39 of the adjacent rack tooth 24 and will axially rotate the member 25 within the tubular member 31 from the position shown in Fig. 4 of the drawing to the position shown in Fig. 5. 100 This rotation of the member 25 will cause the rack teeth 24 to pass out of engagement with the dogs or pawls 27—22, thereby releasing the member 25, which latter, being then unsupported, will start to descend by 105 the force of the gravity thereof. This position of the teeth 24 of the member 25 with respect to the operating pawl will also prevent the storing of further energy while the stored energy is being expended. 110

During the descent of the member 25, the lugs or projections 34 will strike the extremity 35 of the arm 32 and throw the bell hammer or clapper 30 outward and to the position shown in dotted lines in Fig. 3, and 115 after the adjacent lug or projection 34 has passed the extremity of the arm 32, the gravity of the clapper or hammer 30 will cause the same to fall against and strike the bell 20, thereby sounding the signal. This 120 operation will be repeated according to the number of lugs or projections 34 which are provided on the member 25.

Any suitable means may be provided for 125 restoring or axially rotating the member 25 to its normal position, or to a position that the teeth 24 will be so disposed as to be engaged by the dogs or pawls 27—22 to again raise the member. A suitable and efficient means for accomplishing this purpose com- 130

prises a suitable lug or projection 40, which is preferably arranged adjacent the lower extremity of the tubular member 11, and said lug or projection is adapted to be engaged by a suitable cam face or surface 41 on the extremity of the member 25, which will rotate the member 25 into its operative position as the member reaches the limit of its descent. The member 25 being thus properly positioned, the action or rotation of the pulley 16 will again lift the member 25 in the manner already described.

Any suitable means may be provided for regulating the speed of the fall of the member 25 to control or cause intervals between the sounds of the bell so that the sounds may be distinctly rendered. A suitable and efficient manner for controlling the descent of the member 25 consists in closing the lower end of the tubular member 11 as at 42 so that the lower portion of the tubular member 11 will hold water and said portion will always be full of water due to the loose fit of the member 25 therein and the openings 23-33 in the tubular member. It will thus be seen that when the member 25 descends, the portion of the tubular member 11 which is filled with water will act as a dash pot, as the water cannot be displaced except by passing up the sides of the member 25 and out through the openings 23-33, the member 25 being of a size to substantially fill the tubular member 11, thereby causing the water to offer a resistance against the descent of the member 25. A suitable and efficient means for regulating the speed of the descent of the member 25, preferably comprises a valve or gate 43 adapted to close a suitable aperture or opening 44 in the lower extremity of the tubular member, and this gate or valve 43 may be adjusted to regulate the opening 44 to permit the water to be displaced more rapidly, if desired.

Suitable and efficient means may be provided for holding or locking the bell hammer or clapper 30 directly after the latter has made a stroke, in order to prevent a constant light tapping of the hammer on the bell due to the vibration which will be imparted to the hammer by the action of the water. A suitable and efficient means for accomplishing this purpose comprises a bracket or support 45 which may be secured to the tubular member 11. Pivotally supported to this bracket 45 is a locking member 46 which latter is preferably provided with a bifurcated or cut-away portion 47, which is adapted to receive or stand astride of the bell hammer or clapper rod 30^a, and said locking member is adapted to rest upon a suitable collar or support 48, which latter is secured to the bell hammer or clapper rod 30^a. This collar or support 48 is preferably provided with an upwardly projecting pin

or lug 49 adapted to enter a suitable slot or aperture 50 in the locking member 46 so that when the locking member is in a position to rest upon the collar or support 48, the pin or lug 49 will project into the slot or aperture 50 to hold the bell hammer or clapper against vibration. The locking member 46 is also provided with a bifurcated portion 51 which preferably projects on the opposite side of its point of pivotal support, and disposed within said bifurcated portion 51 is a suitable bar or rod 52 which is preferably provided with tappets 53-54 disposed on each side of the bifurcated portion 51, so that when the rod or bar 52 is lowered, the tappet 53 will engage the bifurcated portion 51 to move the locking member 46 about its point of pivotal support in one direction and when raised the tappet 54 will engage said portion to move the locking member 46 in the opposite direction. This bar or rod 52 is pivotally connected at its free end to the arm 32 so that the locking member 46 will be controlled by the action of the arm 32. It will thus be seen that during the descent of the member 25 the lugs 34 will serve first to unlock the bell hammer or clapper, and then move the latter about its point of pivotal support. The locking member 46 is of any suitable light material and of a size to present an extended area to the resistance of the water, but is of sufficient weight as to tend to resume its normal position, but inasmuch as it presents a large area to the water, it will fall there through at a much lower rate of speed than the bell hammer. With this construction the bell hammer will impart a blow to the bell and recover while the locking member 46 is descending to a position to permit the lug or pin 49 to enter the slot or aperture 50 to lock the bell hammer or clapper 30 away from engagement with the bell.

The weight 38 is preferably heavy enough to hold the buoy 10 in approximately the position shown in Fig. 1 of the drawing during ordinary weather, but when a strong current is running, the weight 38 may be drawn upwardly toward the pulley 16, and in order to prevent this weight from coming to a stop in too forcible a manner by striking a portion of the apparatus, and thereby straining the other portions thereof, a suitable and efficient means is provided for cushioning the weight so as to relieve the jar. This cushioning device preferably consists of a cylindrical member 56 which is supported by the bracket 21 and is provided with a closed top 57, having an aperture 58 through which the flexible member 36 passes. The lower extremity of this cylindrical member 56 is preferably open and provided with a flared mouth adapted to direct the upper extremity of the weight 38 therein. The diameter of the upper portion of the

cylindrical member 56 is preferably of a size slightly larger than the diameter of the upper portion of the weight 38, so that when the weight 38 rises sufficiently to enter the cylinder 56, water will be confined therein, and as the aperture 58, which forms an outlet for the water, is comparatively small, the water will only pass through said aperture gradually and thereby form a cushion 10 and relieve the frame or bracket 21 from undue shocks.

In order that the invention might be fully understood by those skilled in the art, the details of the foregoing embodiment thereof have been thus specifically described, but 15

What I claim as new and desire to secure by Letters Patent is:—

1. In a sub-marine sound producing device, means actuated by the movement of the 20 water for generating and storing power including an intermittently reciprocating gravity member, and gravity operated means for utilizing the stored power to intermittently actuate said device.

2. In a sub-marine signal device, the combination of a sound producing member, an intermittently reciprocating gravity member, power generating means actuated by the movement of the water, lifting means actuated by the power generating means and coöperating with the gravity member to raise it to store the power generated, tripping means for releasing the gravity member from its raised position, and striking 35 means actuated by the released gravity member and coöperating with the sound producing member to produce sounds.

3. The combination of a buoyant member and a sub-marine signal device supported 40 thereby comprising a sound producing member, an intermittently reciprocating gravity member, power generating means actuated by the movement of the water, lifting means actuated by the power generating means and coöperating with the gravity member to raise it to store the power generated, tripping means for releasing the gravity member from its raised position, and striking 45 means actuated by the released gravity member and coöperating with the sound producing member to produce sounds.

4. The combination of a buoyant member and a sub-marine signal device supported 55 thereby comprising a sound producing member, means actuated by the movement of the water for generating and storing power including an intermittently reciprocating gravity member, means for arresting the storing of power, and gravity operated 60 means coöperating with the sound producing member for utilizing the stored power to produce sounds.

5. The combination of a buoyant member and a sub-marine signal device supported 65 thereby comprising a sound producing mem-

ber, an intermittently reciprocating gravity member, a lateral extension upon the gravity member, power generating means actuated by the movement of the water, lifting means actuated by the power generating means and coöperating with the gravity member to raise it to store the power generated, tripping means for releasing the gravity member from its raised position, and striking means actuated by the lateral extension 70 upon the released gravity member and coöperating with the sound producing member 75 to produce sound.

6. The combination of a buoyant member and a submarine signal device supported 80 thereby comprising a sound producing member, a gravity member, a plurality of lateral extensions upon the gravity member, power generating means actuated by the movement of the water, lifting means actuated by the power generating means and coöperating with the gravity member to raise it to store the power generated, tripping means for releasing the gravity member from its raised position, and striking means actuated by the lateral extensions 85 upon the released gravity member and coöperating with the sound producing member to periodically produce sound.

7. The combination of a buoyant member 90 and a submarine signal device supported thereby comprising a sound producing member, a gravity member, a plurality of lateral extensions upon the gravity member, power generating means actuated by the movement 95 of the water, lifting means actuated by the power generating means and coöperating with the gravity member to raise it to hold the power generated, tripping means for releasing the gravity member from its raised 100 position, and striking means actuated by the lateral extensions upon the released gravity member and coöperating with the sound producing member to intermittently produce sound.

8. In a sub-marine signal device, the combination of a sound producing member, a gravity member having upon its side a plurality of lateral notches vertically disposed with relation to each other, power generating means actuated by the movement of the water, a plurality of lateral extensions upon the gravity member vertically disposed with relation to each other, a reciprocating lifting pawl actuated by the power generating 115 means and coöperating successively with the notches in the gravity member to raise it step by step to store the power generated, a detent coöperating successively with the notches in the gravity member to hold it in 120 its raised position during each downward reciprocation of the lifting pawl, tripping means for releasing the gravity member from its raised position, and striking means actuated by the lateral extensions upon the 125 130

released gravity member and coöperating with the sound producing member to produce sounds.

9. In a sub-marine signal device, the combination of a sound producing member, a gravity member having upon its side a plurality of lateral notches vertically disposed with relation to each other, power generating means actuated by the movement of the water, a plurality of lateral extensions upon the gravity member vertically disposed with relation to each other, a reciprocating lifting pawl actuated by the power generating means and coöperating successively with the notches in the gravity member to raise it step by step to store the power generated, a detent coöperating successively with the notches in the gravity member to hold it in its raised position during each downward reciprocation of the lifting pawl, an oblique friction surface upon and adjacent the lower extremity of the gravity member and coöperating with the lifting pawl to oscillate the gravity member upon its vertical axis to turn the notched portion thereof out of coöperative relation to said lifting pawl and detent and release it from its raised position, and striking means actuated by the lateral extensions upon the released gravity member and coöperating with the sound producing member to produce sounds.

10. In a sub-marine signal device, the combination of a sound producing member, a gravity member having upon its side a plurality of lateral notches vertically disposed with relation to each other, power generating means actuated by the movement of the water, a plurality of lateral extensions upon the gravity member vertically disposed with relation to each other, a reciprocating lifting pawl actuated by the power generating means and coöperating successively with the notches in the gravity member to raise it step by step to store the power generated, a detent coöperating successively with the notches in the gravity member to hold it in its raised position during each downward reciprocation of the lifting pawl, an oblique friction surface upon and adjacent the lower extremity of the gravity member and coöperating with the lifting pawl to oscillate the gravity member upon its vertical axis to turn the notched portion thereof out of coöperative relation with said lifting pawl and detent and release it from its raised position, striking means actuated by the lateral extensions upon the released gravity member and coöperating with the sound producing member to produce sounds, a casing in which the gravity member is mounted for vertical reciprocation and oscillation about a vertical axis, an oblique cam surface upon the gravity member, an inwardly projecting stud upon the casing coöperating with the oblique cam surface to oscillate the gravity

member upon its vertical axis into coöperative relation to the lifting pawl and the detent when the gravity member has completed its downward stroke.

11. In a sub-marine signal device, the combination of a sound producing member, a gravity member, an approximately closed casing in which said gravity member is mounted for vertical reciprocation, power generating means actuated by the movement of the water, lifting means coöperating with the gravity member to raise it adjacent the upper extremity of said casing to store the power generated, tripping means for releasing the gravity member when it has reached a predetermined elevation, striking means coöperating with the gravity member for utilizing its downward stroke to actuate the sound producing member, and means adjacent the lower extremity of the casing for regulating the speed of the downward stroke of said gravity member.

12. The combination of a buoyant member and a submarine signal device supported thereby comprising a sound producing member, a vertically reciprocating gravity member, striking means actuated by the downward stroke of said gravity member and coöperating with said sound producing member to produce sound, power generating means for utilizing the movement of the water to elevate the gravity member, a casing of approximately the same diameter as the gravity member in which the gravity member reciprocates and having an opening adjacent its lower extremity admitting water into the casing during the upward stroke of the gravity member and emitting water from the casing during the downward stroke of the gravity member, and means coöperating with the opening adjacent the lower extremity of the casing for regulating the efflux of water therefrom.

13. The combination of a buoyant member, an anchor to which the buoyant member is movably secured, power generating means operatively joined to and actuated by the relative movement between the buoyant member and the anchor, a vertically reciprocating gravity member raised by the power generating means, a sub-marine sound-producing member, a striking member coöperating with the sound-producing member to produce sound, and a lateral extension upon the gravity member coöperating with the striking member during the downward stroke of the gravity member to actuate said striking member.

14. The combination of a buoyant member, an anchor to which the buoyant member is movably secured, a sub-marine sound-producing device supported by the buoyant member, a striking member coöperating with the sound producing member to produce sound, power generating means op-

simultaneously releasing the gravity member for downward reciprocation, and a plurality of lateral extensions upon the gravity member coöperating with the striking member during the downward reciprocation of the gravity member to simultaneously unlock and actuate the striking member.

22. The combination of a buoyant member, a submarine sound-producing device supported thereby, a striking member coöperating with the sound-producing member to produce sound and normally locked in an inoperative position, a vertically reciprocating gravity member, power generating means actuated by the movement of the water, lifting means actuated by the power generating means and coöperating with the gravity member to elevate it to store the power generated, a cam surface upon the gravity member engaging the lifting means for turning the gravity member from operative contact with the lifting means and simultaneously releasing the gravity member for downward reciprocation, a casing in which said gravity member reciprocates, an inwardly protruding stud upon and adjacent the lower extremity of said casing and coöperating with said cam surface to return the gravity member into operative relation to the lifting means at the completion of the downward reciprocation of the gravity member.

23. The combination of a buoyant member, a submarine signal device supported thereby, an anchor, a rotary member upon the signal device, a connection movably securing the signal device to the anchor and operatively related to the rotary member for generating power from the relative movement between the signal device and the anchor, an intermittently reciprocating gravity member lifted and released by the power generated and adapted to coöperate a plurality of times in its descent with the signal device to produce sounds.

24. The combination of a buoyant member, a sub-marine signal device supported thereby, an anchor, a movable member connecting the anchor and the signal device, means actuated by the movement of the buoyant member for generating and storing power including an intermittently reciprocating gravity member and gravity actuated means for operating the signal device to produce sound.

25. The combination of a buoyant member, a sub-marine sound-producing signal supported thereby including a sounding device, a movable member, an anchor having engagement with the movable member for oscillating the movable member when the buoyant member is moved, an actuating member for the sounding device lifting means actuated by the movable member and coöoperating with the actuating member to

elevate it, a striking member coöperating with the sounding device to produce sound, and extensions upon the actuating member coöperating with the striking member to actuate the striking member.

70

26. The combination of a buoyant member, a sub-marine sound-producing signal supported thereby including a sound-producing device and a gravity member for actuating said device, a rotary member, an anchor having connection with the rotary member whereby an oscillating motion will be imparted to the rotary member when the buoyant member is moved, means operatively related to the rotary member for adjusting the gravity member and releasing the gravity member to sound the signal, and means for retarding the movement of the gravity member when released.

27. The combination of a buoyant member, a sub-marine sound-producing signal supported thereby including a sound device and a gravity member for actuating said device, a rotary member, an anchor having connection with the rotary member whereby an oscillating motion will be imparted to the rotary member when the buoyant member is moved, means operatively related to the rotary member for adjusting the gravity member and releasing the gravity member to sound the signal, and a dash pot adapted to receive the gravity member to retard its movements when released.

28. The combination of a buoyant member, a sub-marine sound-producing signal supported thereby including a sounding device, a gravity member for actuating the sounding device, a rotary member, a flexible member anchored at one of its ends and engaging the rotary member intermediate its ends, a weight secured to the free end of the flexible member whereby an oscillatory motion is imparted to the rotary member when the buoyant member is moved, a cushioning device for the weight and means operatively related to the rotary member for adjusting the gravity member and releasing it to sound the signal.

29. A sub-marine sound-producing signal including a sounding device and a gravity member for actuating the same, a pivotally supported member, means actuated by the movement of the water for oscillating the pivotally supported member, a rack upon the gravity member, a lifting pawl coöperating with said rack and actuated by the pivotally supported member for adjusting the gravity member, a retaining pawl engaging the rack upon the gravity member, an oblique friction surface upon and adjacent the lower extremity of the gravity member with which the lifting pawl coöperates to release the gravity member from its adjusted position, a series of extensions upon the gravity member, a striking mem- 120
125
130

ber coöperating with the sounding device to produce sound and actuated by said lateral extensions during the downward movement of the gravity member.

5 30. A sub-marine sound-producing signal including an intermittently reciprocating gravity member for actuating the signal, a pivotally supported member, means actuated by the movement of the water for oscillating the pivotally supported member, and pawl and rack apparatus actuated by the pivotally supported member for adjusting the gravity member to an operative position and releasing it to operate the signal.

10 15. 31. A sub-marine sound-producing signal including a gravity member for actuating the signal, a pivotally supported member, means actuated by the movement of the water for oscillating the pivotally supported member, and pawl and rack apparatus actuated by the pivotally supported member and including two cams and a fixed stud for adjusting the gravity member to an operative position and for displacing 20 25 the rack portion of the pawl and rack apparatus with respect to the pawl portion to release the gravity member to operate the signal.

30 32. A sub-marine sound-producing signal including a gravity member for actuating the signal, a pawl and rack construction actuated by the movement of the water and including two cams and a fixed stud to adjust the gravity member to an operative position 35 and to displace the rack portion of the pawl and rack apparatus with respect to the pawl portion to release the gravity member to sound the signal, and means for returning the pawl and rack portions to their operative position after the signal has been sounded.

40 33. A sub-marine sound-producing signal including a gravity member for actuating the signal, a pawl and rack construction actuated by the movement of the water and including two cams and a fixed stud to adjust 45 the gravity member to an operative position and to displace the rack portion of the pawl

and rack apparatus with respect to the pawl portion to release the gravity member to sound the signal, and an interengaging cam surface and projection for returning the pawl and rack portions into operative relation.

50 34. A submarine sound producing signal including a gravity member for actuating the signal, said member being provided with rack teeth, a pawl adapted to engage the teeth, means actuated by the action of the water for operating the pawl to move the gravity member into an operative position, 55 one of said teeth being provided with an inclined face adapted to be engaged by the pawl to automatically axially rotate the gravity member to displace the teeth and release said member to operate the signal, and means 60 65 for rotating the gravity member after the signal has been sounded to place the teeth in an operative position with relation to the pawl.

70 35. A submarine sound producing signal including a gravity member for actuating the signal, said member being provided with rack teeth, a pawl adapted to engage the teeth, means actuated by the action of the water for operating the pawl to move 75 the gravity member into an operative position, one of said teeth being provided with an inclined face adapted to be engaged by the pawl to automatically axially rotate the gravity member to displace the teeth and 80 release said member, means operatively related to the gravity member for intermittently sounding the signal during its movement while released, and means for rotating the member to replace the teeth in an 85 operative position with relation to the pawl when said member has substantially reached the limit of its movement while released.

90 In testimony whereof I have signed my name to this specification, in the presence of two subscribing witnesses, on this 14th day of May A. D. 1907.

GEORGE A. LOWRY.
